MECHANICAL ADJUSTABLE WHISTLE

Theodor Ruhmann, Brooklyn, N. Y.

Application November 19, 1936, Serial No. 111,696

5 Claims. (Cl. 84—330)

This invention relates to whistles and has for its main object to provide a whistle in which the pitch, character, value, etc. of the tone may be changed while playing, in a novel, efficient, easy manner.

Another object of this invention is to provide a whistle of this character in which said changes may be made in an automatic or semi-automatic manner by mechanical means.

10 Still a further object of this invention is to provide a mechanical whistle of this type in which the said changes may be effected by the organs and parts of the mouth of the player easily, quickly and effectively without removing the

15 whistle from the mouth or manipulating it in any other manner.

Still another object of this invention is to provide a mechanical automatic or semi-automatic whistle wherein a substantially ordinary simple whistle is enabled to play complicated tunes involving great variations in tone, sound and pitch.

Other objects of this invention will be apparent as the specification of the same proceeds, and among others I may mention: to provide a whistle as characterized hereinbefore which will be simple in construction, inexpensive to manufacture, adapted to mass manufacturing, easy and reliable to operate, and which will not get out of order and will have long wearing qualities.

20 In the drawings forming a part of this specification, and accompanying the same:

Fig. 1 is a sectional elevation of my assembled whistle showing it as being operated by a player;

Fig. 2 is a side elevation thereof, part of it being broken away, and

Fig. 3 is a partly sectional plan view.

Referring now to the drawings more closely, by characters of reference, the main body of my whistle or the whistle proper is indicated in general by the numeral 10, and it is a hollow body open at both ends, in the embodiment shown in the drawings being substantially rectangular in cross-section, and having a bottom wall 11, a top wall 12, a right-hand wall 13 and a left-hand side wall 14. The bottom wall 11 is somewhat curved and is forwardly shorter than the top wall 12, and the major portion of the body 10 is closed by a front wall or partition 15 from which is projecting an upper front bottom wall 16, having a slight inclination towards the top wall 12, the forward ends of the two forming a narrow sound producing opening 17, as will be understood.

To the forward ends of the side walls 13 and 14 is secured a transverse hollow cylindrical body 18, being entirely closed by its two end walls 19

and 20, and having a narrow longitudinal opening or recess 21 in its upper surface, adjacent to and in front of the opening 17 of the whistle proper. A comparatively heavy shaft 22 is journaled in the end walls 19 and 20 of the hollow cylinder 18 in the center axis thereof, and a radially projecting partition wall 23 is secured on the shaft, rotatable therewith and reaching to the outer wall of the cylinder 18 and to the side walls 19 and 20 thereof. The outer end of the radial rotating partition 23 may have a slidable but sealing engagement with the wall of the cylinder 18, as by the leather seal 24.

A second, stationary, radial partition wall 25 is secured in the wall of the cylinder 18, preferably adjacent and rearward to the recess or opening 21, having slidable but sealing engagement with the shaft 22, as indicated at 26.

A second shaft 27 is also arranged in my whistle, transverse in the body 10 thereof, and journaled in the side walls 13 and 14, as at 28 and 29.

An operating plate lever 30 is secured on the shaft 27, as by the screw threads 31, and the right-hand end 32 of said shaft is continued in an arm 33, curved as shown, reaching towards the front and the shaft 22 of my whistle. A flexible resilient band 34, of any appropriate material like steel is secured to the shaft 22 and wound around it at the projecting end 35 thereof as at 36, while the other end of the band 34 is secured to the free end of the arm 33 by any appropriate means, as through the agency of a cylindrical hollow body 37, in the manner indicated in Figs. 2 and 3, so that an easily flexible resilient connection is established between the end 35 of the shaft 22 and the free end 38 of the arm 33.

A cylindrical housing 39 is provided for the shaft end 35, having a cover 40 and a cut out portion 41, to allow for the play of the band 34.

The left-hand end 42 of the shaft 22 is also projecting beyond the opposite end wall 20, and is arranged in a housing 43 with a cover 44, and a spiral spring, generally indicated by the numeral 45, is engaging said end of the shaft, being secured thereto, as at 46, and to the housing 43, as at 47, respectively.

It will be obvious that the tendency of the spring 45 will be to return the shaft to its original position after it has been rocked and the rocking force removed.

The rearward end of the upper wall 12 of the whistle body and the adjacent portions of the side walls 13 and 14 are upwardly curved, as at 48, and a transverse lug or projection 49 is provided

on its upper surface, in front of said upward bend. The bottom wall 11 terminates rearwardly also somewhat before the termination of the upper wall 12, and has a transverse enlargement or lug 59 at its rear end. The plate level 30 is projecting rearwardly through the opening of the body 10, as at 51, and also has a transverse projection or lug 52 on its lower surface.

The use and operation of my device is as follows: The rearward wider end of the whistle is inserted into the mouth of the player, as indicated in Fig. 1, the upper lip 53 preferably resting against the upper lug or transverse projection 49, while the lower lip 54 will rest against the 15 lug or projection 50, at the end of the bottom wall 11, the rear opening 55 of the whistle being entirely sealed against outside interference with in the mouth of the player. The upper teeth 56 preferably may rest against the rear surface of 20 the projection 49, while the lower teeth 57 of the player engage the extension 51 of the plate arm 30 and may rest against the transverse projection 52 on its lower surface.

The player will blow a current of air through 25 the whistle from the rear thereof, as will be understood, and as indicated by the arrow 58, and the air will produce a sound at the narrow front end 17 thereof. While the sound is produced by the whistle, the lower teeth 57 may 30 operate the plate lever or arm 30 and move it upwardly to a desired degree, as indicated by the arrow 59, while the rest of the whistle, and the rest of the parts of the mouth engaging it, remain stationary. The upward moving of the 35 plate arm 30 will cause the shaft 31 to rock and the arm 33 to move downwardly, in the direction of the arrow 60, which movement will unwind a portion of the band 34 from the shaft 22 and cause the shaft 22 to rock, thereby moving the 40 partition wall 23 in the hollow cylinder 13 in a forward direction, as indicated by the arrows 61. The amount of the forward movement of the partition wall 23 will influence and change the 45 amount of space between said partition wall 23 and the upper opening 21 in the hollow cylinder 13, and the change of that space will influence the sound produced at the opening 17. Generally, the smaller the said space the higher and more shrill will be the voice of the whistle, and 50 the larger the said space the lower will be the tone of the whistle.

As soon as the lower teeth 57 relax their pressure on the plate arm 30, spring 45 will automatically rock the shaft 22 in the opposite direction and will return the partition wall to its 55 original position, as indicated in Fig. 1, so that an upward movement of the plate arm 30 will make the tone higher, and the relieving of the pressure on said plate arm will make the tone 60 of the whistle lower and deeper. In this manner an infinite variety of tones may be produced in an extremely simple manner on my whistle from a very high and shrill one to a very low and deep one.

65 Two longitudinal walls 63 may be placed at the two sides of the opening 21 to aid in the producing of the sound, and a rubber cover or bag 64 may be pulled over the operative end 51 of the plate arm 30 to protect the lower teeth 57.

70 What I claim as new, is:

1. In a whistle, having a hollow body one end of which is adapted to be inserted into the mouth of the player to blow a current of air there-through, the other end having an exit opening 75 to produce the sound, a closed hollow body se-

cured to the sound producing end thereof, having a sound modulating opening adjacent to said sound producing opening of the whistle, and means in said hollow body to vary its volume of space connected with said modulating opening; said closed hollow body being in the form of a hollow cylinder, and said means comprising an axial shaft journalled in the end walls of said hollow cylinder, a radial partition wall projecting from said shaft and rotatable therewith, the outer end thereof being in sliding but sealing engagement with the walls of said hollow cylinder, and a stationary radial partition wall the outer end of which is secured to the wall of the cylinder, the inner end being in sealing but sliding engagement with said shaft.

2. In a whistle, having a hollow body one end of which is adapted to be inserted into the mouth of the player to blow a current of air there-through, the other end having an exit opening 20 to produce the sound, a closed hollow body secured to the sound producing end thereof, having a sound modulating opening adjacent to said sound producing opening of the whistle, and means in said hollow body to vary its volume of space 25 connected with said modulating opening; said closed hollow body being in the form of a hollow cylinder, and said means comprising an axial shaft journalled in the end walls of said hollow cylinder, a radial partition wall projecting from said shaft and rotatable therewith, the outer end thereof being in sliding but sealing engagement with the walls of said hollow cylinder, and a stationary radial partition wall the outer end of which is secured to the wall of the 30 cylinder, the inner end being in sealing but sliding engagement with said shaft; a member operated by an organ in the mouth of the player and a connection between said member and said shaft to rock the shaft by the movement of said 40 member.

3. In a whistle, having a hollow body one end of which is adapted to be inserted into the mouth of the player to blow a current of air there-through, the other end having an exit opening to 45 produce the sound, a closed hollow body secured to the sound producing end thereof, having a sound modulating opening adjacent to said sound producing opening of the whistle, and means in said hollow body to vary its volume of space connected with said modulating opening; said closed hollow body being in the form of a hollow cylinder, and said means comprising an axial shaft journalled in the end walls of said hollow cylinder, a radial partition wall projecting from said shaft and rotatable therewith, the outer end thereof being in sliding but sealing engagement with the walls of said hollow cylinder, and a stationary radial partition wall the outer end of which is secured to the wall of the cylinder, the inner end being in sealing but 50 sliding engagement with said shaft; a member operated by an organ in the mouth of the player and a connection between said member and said shaft to rock the shaft by the movement of said 55 member; and a second shaft in the whistle body, said member being in the form of an arm rotatable with said second shaft and adapted to project into the mouth of the player.

4. A mechanical whistle comprising a substantially prismatic hollow body, one end being adapted to be inserted into the mouth of the player, to blow an air current therethrough, the other, front end being open and adapted to produce a sound, a closed hollow cylinder secured on the front end of said whistle body, transversely thereof and 75

substantially underneath said sound producing opening, said hollow cylinder having a longitudinal modulating opening in front of said sound producing opening and in connection with a space within said hollow cylinder, a shaft in the axis of said cylinder journaled in its end walls, a rotating partition wall radially secured on said shaft for the whole length of said cylinder, being in sliding but sealing engagement with the walls thereof; a second stationary radial partition wall secured into the outer wall of said cylinder adjacent to and in the rear of said modulating opening, traversing the entire length of the cylinder, and being in a sliding but sealing engagement 10 with said shaft, a second shaft journaled in the side walls of the whistle body transversely there-

of, a lever secured on said second shaft, rockable therewith, its free end adapted to project into the mouth of the player and being adapted to be operated by the lower teeth, a yielding resilient connection between said second shaft and said first shaft whereby the upward movements of said lever arm will be transmitted to said first shaft, and means to automatically return said first shaft upon the release of said lever arm. 5

5. In a mechanical whistle as set forth in claim 10 4, said connection comprising a second arm at one end of said second shaft, and a flexible resilient band secured to said first shaft and to the free end of said second arm, respectively.

15
THEODOR RUHLMANN.
